US00D809563S

(12) **United States Design Patent** (10) Patent No.: **US D809,563 S**
Chaudhri et al. (45) Date of Patent: **** Feb. 6, 2018**

(54) **DISPLAY SCREEN OR PORTION THEREOF WITH GRAPHICAL USER INTERFACE**(71) Applicant: **Apple Inc.**, Cupertino, CA (US)(72) Inventors: **Imran Chaudhri**, San Francisco, CA (US); **Alan C. Dye**, San Francisco, CA (US); **Jonathan P. Ive**, San Francisco, CA (US); **Christopher Daryl Soli**, Mountain View, CA (US)(73) Assignee: **Apple Inc.**, Cupertino, CA (US)(**) Term: **15 Years**(21) Appl. No.: **29/583,583**(22) Filed: **Nov. 7, 2016****Related U.S. Application Data**

(63) Continuation of application No. 29/501,102, filed on Sep. 1, 2014, now Pat. No. Des. 771,123.

(51) **LOC (11) Cl.** ..... **14-04**(52) **U.S. Cl.**USPC ..... **D14/492**; D14/489(58) **Field of Classification Search**

CLAIM

The ornamental design for a display screen or portion thereof with graphical user interface, as shown and described.

DESCRIPTION

The FIGURE is a front view of a display screen or portion thereof with graphical user interface showing the claimed design.

The broken lines in the FIGURE show a display screen or portion thereof, and form no part of the claimed design.

1 Claim, 1 Drawing Sheet(56)
